UNITED STATES PATENT OFFICE.

EDGAR P. GUPTILL, OF WHITINSVILLE, MASSACHUSETTS.

HIP-COVERING FOR ROOFS.

1,262,783.

Specification of Letters Patent.

Patented Apr. 16, 1918.

Application filed January 18, 1918. Serial No. 742,885.

To all whom it may concern:

Be it known that I, EDGAR P. GUPTILL, a citizen of the United States, residing at Whitinsville, in the county of Worcester, State of Massachusetts, have invented a certain new and useful Improvement in Hip-Coverings for Roofs, of which the following is a specification, reference being had thereto in the accompanying drawings.

10 This invention relates to building materials but more particularly to hip covers for roofs.

The device is adapted for use with any form of roofing but will here be treated only 15 as preferably applied to a slate or shingle roof. The object of the same is to provide a cover which will not only absolutely prevent leakage at the hip of the roof but will be attractive in appearance, inexpensive and 20 can be readily put on.

One feature of the invention is the interlocking of segments which absolutely prevents any warping apart of the same. Many other features will be fully set forth hereinafter and included in the claim.

One embodiment of the invention is shown in the drawings in which:—

Figure 1 is a perspective view of the hip of a shingle roof showing the invention applied thereto.

Fig. 2, bottom view of a shingle segment of the hip cover.

Fig. 3, same as Fig. 2, but with two segments interlocked.

35 Fig. 4, sectional view of a roof with the hip cover thereon, the section being taken through the hip cover along the line 4—4 of Fig. 2.

Fig. 5, section of roof showing side elevation of hip cover thereon.

Fig. 6, section on line 6—6 of Fig. 4.

Fig. 7, detail view, as will be described fully hereinafter.

Referring to the drawings, the invention 45 is there shown adapted to an ordinary shingle roof in which shingles 10 are secured upon the house frame 11. The detail form of the invention is best shown by the single section 12 in Fig. 2 comprising an upper portion 13 and a lower portion 14. The portion 14 has each side edge 15 turned downward and then inward forming faces 16 to resemble the edges of a shingle, and inwardly turned flanges 17 which are adapted to interlock with the side edges 18 of the

upper portion of the next section. Two sections interlocking in this manner are shown in Fig. 3 of the drawings.

The sections are secured upon the hip in 60 the following manner, beginning at the bottom:—In starting, as there is no section below to provide an upper portion 13 to interlock with the turned under edges of the lower portion of this first section, it is 65 advisable to nail to the bottom edge of the hip a plate 13' as shown in Fig. 7, corresponding to the portion 13 of a section. Next place the first section with the end edge 19 of the interlocking flanges 17 under the corners 20' 70 corresponding to the corners 20 of the upper portion 13 formed by slitting the section on each side preferably at the junction of the two portions. Now slide the section upwardly along the plate 13' until this plate is 75 beneath the lower portion of the same in substantially the position shown for the part 13 corresponding thereto in Fig. 3 and the edge 19 preferably in contact with the base 21 of the second row of shingles. Then nail 80 down the upper portion of this section by putting nails 22 or other fasteners through the holes 23.

The second section is fitted over the first section by sliding the edge 19 through the 85 slit 24 and then moving the former relative to the portion 13 of the latter as first section was moved relative to the plate 13' in the first operation. Each section thereafter would be added in the same manner as the 90 second section until the top of the hip was reached.

The base edge 25 of the section 12 is preferably turned downwardly as best shown in Fig. 4 to give the cover the appearance of 95 being made of shingles. The downward turn of the side edges of the section to form the faces 16 and of the corresponding base edge 25 would be omitted if the cover was to be used with a flat roofing and the side edges 100 would be merely turned under to form the inwardly projecting flanges to interlock with the flat portion of the next section as described.

In this construction the nail holes in one 105 section are covered by the overlapping portion of the next higher section so that there is no opportunity for leakage.

The applicant is aware that a considerable number of changes in the construction 110 and arrangement of parts could readily be

made by anyone skilled in the art without departing from the scope of his invention, and he does not care to be limited to the particular embodiment shown in the drawings and 5 described in the specification.

What I claim as my invention and desire to secure by Letters Patent is:—

A hip covering for roofs comprising a series of sections each composed of a plate 10 having each of its side edges slitted transversely intermediate its ends with the side edge portions below the slits turned to form

a locking flange and the side edge portions above the slit not so turned, the latter portions being nailed at points spaced from the edges thereof a sufficient distance to permit the locking flange of the next upper section to interlock with said portions. 15

In testimony whereof I affix my signature in the presence of two witnesses.

EDGAR P. GUPTILL.
